BOTTLE COVER OR SIMILAR ARTICLE

Alan R. Fairlie, 417 Queensberry Road,
Edinburgh 4, Scotland

Filed May 15, 1969, Ser. No. 17,157

Claims priority, application Great Britain Nov. 20, 1968

Term of patent 14 years

Int. Cl. D9—99

U.S. Cl. D9—259

FIG. 1 is a perspective view of a bottle cover or similar article showing my new design;

FIG. 2 is an enlarged sectional view taken on the line 2—2 of FIG. 1; and

FIG. 3 is an enlarged sectional view taken on the line 3—3 of FIG. 1.

The bottle cover is shown in the form it would take when placed on a bottle.

I claim:

The ornamental design for a bottle cover or similar article, as shown and described.
